RELAY DEVICE

Arthur Greenwood Kershaw, London, England,
assignor, by mesne assignments, to The Union
Switch & Signal Company, Swissvale, Pa., a
corporation of Pennsylvania

Application September 10, 1937, Serial No. 163,284
In Great Britain January 7, 1937

3 Claims. (Cl. 200—168)

This invention relates to relay devices and the like of the kind in which the contacts of the device are arranged to be connected to the external circuits controlling the operation of the relay device and controlled thereby by means of a detachable terminal board or boards, the terminals of which are connected to the external circuits, the invention having for its object to provide improved arrangements of this character.

10 According to the invention the terminal board or boards is or are arranged to be pivotally mounted on the frame or support carrying the relay device in such a manner that by rotating the terminal board about its pivot the contacts 15 carried thereby and connected to the external circuit terminals are moved out of engagement with the corresponding contacts carried upon the frame or support and connected to the relay contacts thereby enabling the relay device to be removed and replaced.

In order that the invention may be readily understood it will now be described, by way of example only, with reference to the accompanying drawings in which:

Figure 1 is a partly sectional side elevational view and Figure 2 a plan view from below illustrating the invention as applied to one form of relay device, the figures being partly broken away. Figure 3 is a sectional view on the line II—II of Figure 1.

30 Referring to the drawings, the reference character 1 designates a frame which supports a relay device, which relay device may for example be similar to that shown and described in the copending application for Letters Patent of the 35 United States, Serial No. 151,878, filed by myself and another on July 3, 1937 for Electrically operated switch mechanism. This frame is provided at one end thereof with a number of projecting lugs 2 carried by a member 3 suitably 40 secured to the frame 1, each of these lugs 2 being provided with a transverse pivot pin 4 serving to couple the forked end 5 of a bar 6 carrying a terminal board 7 to the lug 2. The 45 opposite end 8 of each of these bars 6 is arranged to fit within a pair of corresponding lugs 9 carried by the base 10 of the relay device, each pair of lugs 9 being provided with a removable transverse pin 11 for securing the end 8 of the bar 6 in position in the lugs 9. The ends 8 of the 50 bars 6 are provided with suitable handles 12 and the terminals 13 on the boards 7 carried by the bars 6 are electrically connected to contacts 14 (Figure 3) which, when the bars 6 are in the 55 positions above described, engage with corresponding contact springs 15 mounted on the base 10 and connected to the fixed relay contacts 16.

It will be understood that by withdrawing the

pins 11 from the pairs of lugs 9, the bars 6 can be rotated around the pivot pins 4 by means of the handles 12 so as to withdraw the contacts 14 on the terminal boards 7 from the contact springs 15 on the base 10 so that the relay device is then 5 disconnected from the external circuits and can be removed and replaced by another relay device.

The invention is evidently not limited to the particular construction above described by way of example which may be modified in various respects without exceeding the scope of the invention.

Having now particularly described and ascertained the nature of my said invention and in what manner the same is to be performed, I declare that what I claim is:

1. In combination, a frame which supports a device having contacts mounted thereon, a plurality of terminal boards pivotally attached at one end to said frame for individual swinging 20 movement toward and away from the contacts of said device, and contacts mounted on each terminal board in such positions that they will become engaged with or disengaged from associated ones of said first mentioned contacts according as the terminal board is swung toward 25 or away from said frame.

2. In combination, a frame which supports a relay device having a base provided with contacts connected to the relay contacts and with a pair of spaced lugs, a bar having a forked end and coupled at one end by means of a transverse pivot pin to a lug carried by said frame and adapted at the other end to fit between the lugs of said pair, a terminal board secured to said bar and provided with contacts which engage the contacts on said base when said bar is between the lugs of said pair, a removable pin mounted in said pair of lugs for securing said bar in the position in which it is between said lugs, and a handle secured to said bar at the end which cooperates with said pair of lugs.

3. In combination, a frame which supports a device having a base provided with contacts and with a pair of spaced lugs, a bar having a forked end and coupled at one end by means of a transverse pivot pin to a lug carried by said frame and adapted at the other end to fit between the lugs of said pair, a terminal board secured to said bar and provided with contacts which engage the contacts on said base when said bar is between the lugs of said pair, a removable pin mounted in said pair of lugs for securing said bar in the position in which it is between said lugs, and a handle secured to said bar at the end which cooperates with said pair of lugs.

ARTHUR GREENWOOD KERSHAW.
